(57) **CLAIM**

The ornamental design for a combined ear muff and safety glasses, as shown and described.

DESCRIPTION

FIG. 1 is a top view of a combined ear muff and safety glasses;

FIG. 2 is a bottom view thereof;

FIG. 3 is a front view thereof;

FIG. 4 is rear view thereof;

FIG. 5 is a left side view thereof, illustrating the safety glasses in a down position;

FIG. 6 is a left side view thereof, illustrating the safety glasses in an up position;

FIG. 7 is a top perspective view thereof; and,

FIG. 8 is a bottom perspective thereof.

1 Claim, 6 Drawing Sheets
